(57) **CLAIM**

The ornamental design for a battery for vacuum cleaner, as shown and described.

DESCRIPTION

FIG. 1 is a front perspective view of a battery for vacuum cleaner, showing our new design;

FIG. 2 is a front view thereof;

FIG. 3 is a rear view thereof;

FIG. 4 is a left-side view thereof;

FIG. 5 is a right-side view thereof;

FIG. 6 is a top plan view thereof;

FIG. 7 is a bottom plan view thereof;

FIG. 8 is an enlarged view of the delineated portion 8 in FIG. 1;

FIG. 9 is an enlarged view of the delineated portion 9 in FIG. 1;

FIG. 10 is an enlarged view of the delineated portion 10 in FIG. 1; and,

FIG. 11 is an enlarged view of the delineated portion 11 in FIG. 1.

The evenly dashed broken lines in the figures depict environmental subject matter and form no part of the claimed design.

The dot-dash broken lines delineating portions of the claimed design that are illustrated in enlargements form no part of the claimed design.

1 Claim, 11 Drawing Sheets
